ELECTRIC LAMP

Clarence W. Gould, Waltham, Mass., assignor,
by means assignments, to Birdseye Electric
Corporation, Gloucester, Mass., a corporation
of Massachusetts

Application April 8, 1938, Serial No. 200,882

3 Claims. (CL 176—35)

This invention relates to electric lamps and consists in a lamp having an exhaust tube communicating with the interior of its bulb and provided with a metallic sealing portion.

Gas-filled lamps as heretofore manufactured have generally been sealed with their gaseous content under less than atmospheric pressure and no difficulty has been experienced in employing the conventional exhaust tube or stem 10 of glass or in sealing such a tube in manufacturing lamps of that kind on a commercial scale. It has been appreciated for some time, however, that the luminous efficiency of electric lamps may be increased by sealing their gaseous content 15 under more than atmospheric pressure, for example, under a pressure of 1½ atmospheres or from 900 to 1000 mm. of mercury. It is impractical to employ an exhausting and filling tube of glass under conditions of internal pressure because a glass tube tends to blow out when softened for sealing. The attempt has been made to overcome this difficulty by enclosing the usual 20 glass exhausting tube within a pressure chamber while sealing it with a flame, in this way equalizing the pressure inside and outside the tube while the glass is in softened condition. This 25 expedient is not satisfactory however, in that it involves elaborate apparatus and seriously slows down the rate of manufacturing production.

The object of the present invention is to overcome the difficulties above discussed and to provide a simple and effective structure by which the bulbs of lamps gas filled at more than atmospheric pressure may be sealed securely and rapidly under commercial conditions of manufacture. To this end an important feature of the invention consists in an electric lamp bulb provided 30 with a tube having a metallic sealing portion therein. The exact construction employed is a matter of secondary importance. A thin metal tube may be sealed in the press of the mount or into the hollow flare, or a short metal tube may be united to a glass stem which is itself sealed either into the flare or the press. An advantage 35 of sealing the tube into the press is that in this location it may be utilized as one of the lead connections to the filament or to an electrode in the bulb. In any case it is desirable to insulate the tube within the bulb to avoid danger of short-circuiting between the lead connections and another feature of the invention consists in a lamp 40 bulb provided with a tube having a metal sealing portion and being protected by suitable insulation from the lead wires of the lamp.

A thin copper tube is suitable for purposes of

this invention since it may be heated to a sealing temperature without reducing its strength to a point where it will be distorted by internal pressure. Other metals may be used and due regard must be paid to the matter of selecting a metal or so treating it as to insure perfect union with the glass of the press or of the flare. In sealing a thin copper tube it is practicable to heat it, compressing its side walls and spot-welding or soldering them together in a gas-tight 10 joint and having thus sealed the tube, its end may be trimmed off preparatory to the basing operation.

These and other features of the invention will be best understood and appreciated from the following description of several preferred embodiments thereof selected for purposes of illustration and shown in the accompanying drawing in which,

Fig. 1 is a fragmentary view in cross section 20 of an incandescent electric lamp bulb in process of being sealed,

Fig. 2 is a fragmentary view in cross section showing the tube as sealed and insulated,

Figs. 3, 4 and 5 are views illustrating alternative forms of exhaust tube, and

Fig. 6 is a fragmentary view of a bulb in which the metal exhaust tube is utilized also as a lead-in connection.

The bulb 10 shown in Fig. 1 is of a type conventionally employed in incandescent electric lamps and has a hollow mount or flare 11 sealed into its neck. The flare terminates in a press 12 into which are sealed the lead and supporting wires 13 which carry the filament 14 at the proper 30 location within the bulb. As shown in Fig. 1 a metal tube 15 of small diameter extends axially into the flare 11 being curved at its inner end and sealed in the inner end of the flare so that it opens into the interior of the bulb. The tube 15 may be of thin copper or of other metal or alloy suitable for sealing to glass. One satisfactory method of forming a union between the metal tube 15 and the glass flare 11 is disclosed in U. S. Letters Patent No. 2,035,015, granted 45 March 24, 1936 on an application of R. E. Schirmer to which reference may be had for details of procedure.

It will be understood that the function of the metal tube 15 is first to exhaust the bulb 10 50 and then fill it with argon or other inert gases or gas mixtures under greater than atmospheric pressure. Having thus filled the bulb, the tube 15 is sealed under pressure. The metal walls of the tube are adapted to be heated to a fusing 55

or soldering temperature without being weakened sufficiently to be distorted by any pressure desired within the bulb. One satisfactory procedure for sealing the tube 15 is suggested in Fig. 1 where cooperating jaws 16 and 17 are shown as mounted for clamping movement adjacent to the end of the neck of the bulb and as connected in electric circuit through which a current may be supplied for spot-welding the collapsed walls 10 of the tube, and so forming an effective gas-tight seal therein. The inner walls of the tube 15 may be tinned if desired and the seal effected by soldering if preferred. At the completion of the sealing step the end of the tube may be 15 severed by cooperating cutters 18 and the sealed bulb is then ready for the basing operation.

In Fig. 2 the end of the tube 15 is shown as sealed in the manner suggested in Fig. 1. The sealed tube is provided with an insulating sleeve 19 of woven asbestos or the like by which it is effectively insulated from the lead wires 18 which pass downwardly from the flare 11.

In Fig. 6 I have shown an alternative construction in which a small metal tube 22 is sealed in the press 12 instead of in the walls of the flare 11 as in Fig. 1. In this construction it is practicable to utilize the metallic tube 22 as one of the lead connections to the filament or to an electrode or other terminal within the bulb. Accordingly one lead wire 21 is shown as passing through the press 12 and the flare 11, while the other lead wire 23 is connected to the inner end of the metal tube 22 and then continued again beyond the outer sealed end of the tube. The metal tube 22 is shown as provided with an insulating sleeve 20 to prevent any danger of short-circuiting between it and the lead wire 21.

In Figs. 1, 2 and 6 I have shown the bulb as equipped with an integral metal tube, but it is within the scope of the invention to employ an exhausting or filling tube having a metal sealing portion and being formed in part of other material, such as glass. In Figs. 3-5 are illustrated composite tubes of this character which may be substituted in place of the integral tubes shown in Figs. 1, 2 or 6. In Fig. 3 the tube has its upper end 25 formed of glass and so curved

that it may be sealed into the inner end of the flare. The glass end 25 is telescopically united with a metal tube or sleeve 26 and extends out from the flare of the bulb in position to be sealed by welding or soldering as already explained. In Fig. 2 the tube comprises an upper glass end portion 27 and a metal tube 28. The lower end of the glass portion is flared and united by a butt weld to the metal section 28. In Fig. 5 the curved glass end is united to the metal tube 28 which 10 may be copper in this instance and may have the thickness of its walls tapered or reduced so as to reduce the area of contact to a minimum. This is advisable where there is any difference between the coefficient of expansion of the metal 15 employed and the glass. In most instances it is advisable to employ a metal such as "Kovar" or other alloys of chromium, iron and copper or nickel and iron which have the same coefficient 20 of expansion as the glass used in the flare. 20

Having thus disclosed my invention and shown preferred embodiments thereof for purposes of illustration but not in any limiting sense, I claim as new and desire to secure by Letters Patent:

1. An electric lamp having a hollow flare 25 terminating in a press, a glass tube sealed into the press, extending out through the open end of the flare and being provided with an outer metallic extension section in which is included a seal, and means for insulating the metallic section of the tube. 25

2. An electric lamp having a bulb with a hollow flare terminating in a press, lead wires within the flare, and a glass filling and exhausting tube 35 located partially within the flare and communicating with the interior of the bulb, said tube having at its outer end a metal section containing a seal and being insulated from said lead wires. 35

3. An electric lamp having a bulb provided 40 with a hollow internal flare, a glass tube sealed in the flare and communicating with the interior of the bulb, and a metallic section secured to the outer end of said glass tube and serving as a longitudinal extension thereof and in which is included a seal spaced beyond the end of the 45 glass tube. 45
